FABRIC ROLL CREEL FOR CLOTH FOLDING MACHINE

Herbert A. Smith, Jr., Charlotte, N.C., assignor to
Golden Bear Manufacturing & Machine, Inc.

Filed Mar. 27, 1974, Ser. No. 455,418

Term of patent 14 years

Int. Cl. D15—08

U.S. Cl. D92—15

FIG. 1 is a perspective view of a fabric roll creel for cloth folding machine, showing my new design;

FIG. 2 is an end elevational view thereof; and

FIG. 3 is a side elevational view thereof.

I claim:

The ornamental design for a fabric roll creel for cloth folding machine, substantially as shown.
